SPOOL

Carl Palmer Park, Manchester, N. H., assignor
to U. S. Bobbin & Shuttle Company 1929,
Providence, R. I., a corporation of Rhode
Island

Application January 22, 1931. Serial No. 510,493

1 Claim. (Cl. 242—118)

This invention relates to improved spools of the type in which there are disc shaped sheet metal heads fastened at each end to a barrel, which ordinarily would be non-metallic, by means 5 of one or more holding tubes which extend through the passages in the barrel and are upset to fit into or outside of passages in the head which register with those in the barrel.

As fine yarn such as silk or rayon is often wound 10 on such spools, the space between the heads and around the barrel must be free from irregularities or openings which might catch the thread and as they are often used for steaming, they should be so made that the heating and cooling, 15 moistening and drying will not distort them.

As now made, the heads have flat faces inside and outside and it is usually considered necessary to interpose a washer of felt or some similar material between the head and the end of the 20 barrel as shown in Patent to Bray, #1,654,525 of January 3, 1928 on steam bobbins.

It is the purpose of this invention to reduce the 25 number of parts, to reduce the weight of the spool and still to provide a spool which at the essential points is strong enough to resist being dropped on the floor or struck against machinery and one in which the joint between the ends of the barrel and the heads is so tightly closed without the interposition of any felt washer that it 30 not only cannot catch the thread but will not open or close with heat and cold or when subjected to alternate wetting and drying.

I accomplish this by using heads in which are 35 circular recesses into which the ends of the barrel fit and by rigidly locking the parts together by one or more holding tubes the ends of which are so fixed to the heads that no loosening is possible.

In the drawing, Fig. 1 is an end elevation of a 40 spool of the type herein described.

Fig. 2 is a vertical sectional view as from the right of line 2—2 of Fig. 1.

Fig. 3 is a vertical sectional view as on the 45 line 3—3 of Fig. 2 looking from the direction of the arrow.

Fig. 4 is a vertical sectional detail showing a 50 modification of the construction.

Fig. 5 is a sectional detail of my preferred construction on an enlarged scale.

Fig. 6 is a view similar to Fig. 5 of a modified 55 construction.

Fig. 7 is a sectional detail similar to Fig. 2 of another modification.

Fig. 8 is an enlarged sectional detail of the 60 construction shown in Fig. 7.

On account of the tubes and heads being made of relatively thin metal, some of the parts are exaggerated and the enlarged views are shown to more clearly show the construction.

In the drawing, B represents the non-metallic 60 barrel of a spool having an axial passage 1 and at spaced intervals around it, other parallel barrel passages 2, 3 and 4.

H and H¹ are disc shaped sheet metal heads each of which has its outer rim rolled outward at 65 40 to form a substantially complete circular channel which on the assembled spool projects away from the barrel.

41 is a boss of circular shape outwardly pressed from the central part of each head concentric 70 with the outer rim but extending out a less distance and of such a size that an end of the barrel fits snugly inside the complementary recess 49.

Through each head and through this boss such as 41 is a central head passage 11 which registers 75 with passage 1 in the barrel and other head passages 12, 13, 14 which register with the barrel passages 2, 3 and 4 in the barrel.

Each head passage such as 11 has a projecting rim at the outside such as 21, 22, 23, 24 so that 80 each of the holding tubes T¹, T², T³, T⁴, each of which passes through a barrel passage and through two head passages, can be expanded or spread so as to fit at each end outside of and around each head passage rim such as 21, 22, 23, 85 24 as a gromet thereby holding the whole assembly together with great firmness.

The outer faces of these gromets 31, 32, 33, 34 should be inside the outer edges of rim 40.

Radial passages 16, 16 from barrel passage 2 90 through tube T² to the outside of barrel B are shown in Fig. 2. Such passages may be used in the other passages or omitted entirely.

In Fig. 4 is shown a modification of the rolled edge of a head 50 wherein the rolled edge 51 extends out at substantially right angles instead of being bent around into a complete circle. 59 is the barrel recess.

In Fig. 6 each head passage such as 61 spreads at 62 outwardly so that the inside of each outer rim of each head passage is larger than the inside at the inner face of the head 63.

As shown, each head passage flares or spreads about forty degrees.

Each tube 60 is forced outwardly or spread at 65 to fit inside the head passage such as 61. 69 is the barrel recess.

In Fig. 7 is shown a spool construction in which each head such as 70 has only one head passage 110 such as 71.

This head passage 71 as shown is in the center and has a rim 72 which extends directly out, the passage being the same size at the outside as it is at the inside.

5 The end 75 of the holding tube 73 is folded around in the form of a gromet 74 thereby holding the head firmly in position. This head 70 is shown as having a boss such as 76 to snugly receive the end 77 of a barrel such as 78 in its 10 recess 79.

I claim:

The combination in a spool; of a non-metallic cylindrical barrel having longitudinal passages;

with two disc shaped heads each made of sheet metal rolled outward at the rim and having an outwardly pressed circular recess in which an end of the barrel fits and through which are passages which register with those in the barrel, 80 there being at the outside of each head a projecting rim around each passage, each passage being larger at the outside than at the inside; and holding tubes each of which extends through a barrel passage and fits around the outside of a 85 projecting head passage rim.
